UNITED STATES PATENT OFFICE

WILLIAM H. SCHULTE, OF TRENTON, NEW JERSEY

DRINKING FOUNTAIN

Application filed April 29, 1932. Serial No. 608,180.

This invention relates to improvements in sanitary drinking fountains of that type in which a jet of water is projected over the fountain bowl and the user drinks directly from the jet, and its object is to provide certain improvements in the construction of such fountains whereby modern sanitary requirements are efficiently and economically met.

For a full understanding of the invention, a detail description of a construction embodying all the features of the invention in their preferred form will now be given in connection with the accompanying drawing forming a part of this specification and the features forming the invention then specifically pointed out in the claims.

In the drawing:—

Figure 1 is a vertical section of the fountain with the valve open, the jet being shown in dotted lines;

Figure 2 is a partial plan view of Figure 1; and

Figure 3 is a detail section similar to Figure 1, showing the parts in normal position with the valve closed.

Referring to the drawing, A is a fountain bowl having at one side an extension 10, preferably elevated above the bowl discharge and formed with side and bottom plates. A shouldered fitting 13 passes through the extension bottom plate and is threaded into a water supply connection valve casing 16, so that the parts may be readily separated for renewals and repairs by merely unscrewing the fitting 13. The bottom plate of extension 10, as shown, is inclined downwardly toward the interior of the bowl for drainage and inclination of the water jet toward the interior of the bowl.

The interior of supply connection valve casing 16 is divided into two chambers by a web member 8 against the lower side of which a supply valve member 17 seats, the valve member 17 having a hollow upward projection 9 provided with lateral ports 5, 6, the former opening at all times into the chamber above web 8, and the latter, 6, opened to the chamber below web 8 only upon movement of valve member 17 away from its seat against

web 8. Valve 17 is held to its seat by a compression spring 19 housed within a cup or tubular extension 22 formed on the lower end of supply valve 17 and a cap nut 20 threaded into the lower end of casing 16. Water is supplied to valve 17 by a passage 7 controlled, as is usual, by a needle or adjusting valve 18, the outer squared end of which is preferably enclosed by a cap nut 23 arranged to prevent unauthorized changes in the adjustment of needle valve 18.

A jet nozzle 12 is slidably mounted in fitting 13 and carries a tappet 21 projecting from its lower end and cooperating with the projection 9 of valve 17 for operation thereof. The valve tappet 21 may, advantageously, be made adjustable by being threaded into the nozzle 12, as shown, and is formed to provide a port 4, opening into the nozzle 12 and connecting with the chamber above web 8.

A lever 11 is pivotally mounted above nozzle 12 by a pivot pin 1 secured in the side plates of bowl extension 10. The lever 11 is preferably bifurcated, as shown, to permit the jet to pass through it and is provided with a downwardly extending lug 3 bearing upon the upper end of nozzle 12 and operating not only to cam the nozzle 12 downward, but also to properly space the lever 11 above nozzle 12 for operation as a nozzle guard member adapted to prevent contamination of nozzle 12 by access of the fingers thereto. The end of lever 11, opposite to pivot 1, carries brackets 24, to which is pivotally secured by pivot pin 2 a cover member 14, of which its inner end forms a cover for the lever 11 and nozzle 12 and its outer end a finger piece for operation of the cover and valve, the cover member 14 being preferably shaped to cooperate with the outer edges of brackets 24 to provide a stop limiting its turning movement thereon. The lever 11 carries also a downwardly extending guard plate 15, which acts not only to close the rear open end of the extension 10 so as to prevent spattering or slopping of the water therethrough, but also to prevent access of the fingers to the nozzle 12, it being aided in this respect by fingers 25 which co-

operate with the bottom of extension 10 to 100

limit the upward movement of guard 15 and lever 11 about pivot pin 1.

The operation of the valve will be understood from a brief description.

5 As shown in Figure 3, spring 19 is holding the valve 17 seated against web 8, shutting off ports 6 from the chamber below web 8 and supply passage 7, and cover 14 is in closed position over the nozzle 12, the cover 14 being weighted to hold it normally in this position on the valve lever 11.

10 The valve is opened into the position shown in Figure 1 for supply of water in a jet over the fountain bowl by operating the finger piece at the outer end of cover 14 downward to raise the cover, and, by continuing pressure, to move lever 11, cam 3 and nozzle 12 downward, causing tappet 4 to overcome the pressure of spring 19 and move valve 17 downward away from web 8, thus opening ports 6 to the chamber below web 8 and supply passage 7. All the ports during this water supply are in the position shown in Figures 1 and 2, in which they remain, until pressure 15 upon the finger piece of cover 14 is released, when the spring 19 returns all the parts to the position shown in Figure 3.

15 It will be understood that the construction shown may be modified within the invention 30 as defined by the claims.

What I claim is

1. The combination with a bowl having an extension at one side, of a jet nozzle movable in the bottom of said extension, a valve lever mounted in said extension and engaging said movable jet nozzle, a valve fitting mounted in said extension below the jet nozzle, a spring pressed valve in said fitting arranged to be opened by the movement of the 35 jet nozzle, and a jet cover pivoted on the valve lever and arranged to uncover the jet and move the valve lever for opening of the valve and to cover the jet on closing of the valve.

2. The combination with a bowl having an 40 extension at one side, of a jet nozzle movable in the bottom of said extension, a valve lever mounted in said extension and engaging said movable jet nozzle, a valve fitting mounted in said extension below the jet nozzle, a spring pressed valve in said fitting arranged to be opened by the movement of the 45 jet nozzle, a jet cover pivoted on the valve lever and arranged to uncover the jet and move the valve lever for opening of the valve, 50 and a cover carried by the valve lever for closing the rear side of the extension on opening the valve.

3. In a fountain, the combination with a 55 bowl, of a water supply valve chamber secured thereto by a hollow fitting, a web dividing the valve chamber, a spring pressed valve seated against the lower side of said web, a nozzle slidably mounted in said fitting, a 60 tappet carried by said nozzle and arranged 65 to engage the upper end of said valve, and

means for operating said nozzle arranged to prevent finger access to said nozzle and normally providing a cover therefor.

4. In a fountain, the combination with a 70 bowl, of a water supply valve chamber secured thereto by a hollow fitting, a web dividing the valve chamber, a spring pressed valve seated against the lower side of said web, a nozzle slidably mounted in said fitting, an adjustable tappet carried by said nozzle 75 and arranged to engage the upper end of said valve, and means for operating said nozzle arranged to prevent finger access to said nozzle and normally providing a cover therefor.

5. In a fountain, the combination with a 80 bowl, of a water supply valve chamber secured thereto by a hollow fitting, a web dividing the valve chamber, a spring pressed valve seated against the lower side of said web, a nozzle slidably mounted in said fitting, 85 a tappet threaded into said nozzle and carried by said nozzle and arranged to engage the upper end of said valve, and means for operating said nozzle arranged to prevent finger access to said nozzle and normally providing a cover therefor.

90 In testimony whereof, I have hereunto set my hand.

WILLIAM H. SCHULTE.
